UNITED STATES PATENT OFFICE.

HOMER MAURICE LAMB, OF WEST FRANKFORT, ILLINOIS.

ADJUSTABLE GUIDE-CLAMP.

1,337,931.

Specification of Letters Patent. Patented Apr. 20, 1920.

Application filed July 20, 1918. Serial No. 245,949.

To all whom it may concern:

Be it known that I, HOMER M. LAMB, a citizen of the United States, residing at West Frankfort, in the county of Franklin 5 and State of Illinois, have invented new and useful Improvements in Adjustable Guide-Clamps, of which the following is a specification.

This invention is an improved adjustable 10 guide clamp for mine and elevator shafts, the object of the invention being to provide an improved clamping device for use at a joint in a guide in a mine or elevator shaft to hold the meeting ends of the guide members 15 in exact alinement with each other and to also secure the guide members to the guide plate so that the guide will be kept plumb and accidents caused by derangement of the guide will be averted.

With the above and other objects in view, 20 the invention consists in the construction, combination and arrangement of devices hereinafter described and claimed.

In the accompanying drawings:—

Figure 1 is an elevation of a guide and 25 guide plate provided with guide clamps constructed and arranged in accordance with my invention.

Fig. 2 is a perspective view of one of the 30 guide members.

Fig. 3 is a similar view showing a modification of the guide member.

Fig. 4 is a similar view showing another 35 modification of the guide member.

Fig. 5 is a horizontal sectional view.

Fig. 6 is a similar view showing a modification.

For the purposes of this specification a 40 guide plate such as is in use in a mine shaft is indicated at 1 and two members of a vertical guide for a cage or elevator car are indicated at 2 arranged in superposed relation and with their opposing ends abutting. The guide plate is preferably made of half 45 inch boiler plate and is of suitable length and width and is secured by lag screws 3 or other suitable fastening devices to a concrete shaft wall or to steel I-beams or otherwise secured to the side of the shaft as conditions 50 may require.

On one side of the guide members and at the joint between the same is a clamping member 4 which comprises a base 5 and an arm 6. The arm is at right angles to the 55 base and is at one end of the base and is arranged midway between opposite sides

thereof so that the base forms a shoulder 7 at opposite sides of the arm. The base bears on the guide plate and the arm 6 of the base is arranged in a recess 8 formed in one 60 side of the meeting ends of the guide members 2. The base of the clamping member 4 is arranged in a gib 9 which is riveted as at 10 or otherwise fixedly and securely fastened on the guide plate, the said gib serving to 65 house and cover as well as to secure the base of said guide member.

On the opposite side of the guide joint from the clamping member 4 is a clamping member 11 which is similar in construction 70 to said member 4 and the arm 12 of which is also rabbeted in the guide members 2 across the joint. The base 13 of the clamping member 11 is slidable on the guide plate 1 and is slidably held in a gib 75 14 which is riveted or otherwise suitably secured on the guide plate and which is provided with a slot 15 to clear the arm 12. A pair of blocks 16 which are arranged in spaced relation are secured by rivets or other suitable means to the guide plate 80 and are provided with alined unthreaded bores. An adjusting screw 17 is slidable in the bores of said blocks and has one end engaged in a recess 18 in the base of the clamping member 11. An adjusting nut 20 has threaded engagement with the screw and is arranged between the blocks 16 and may be turned by means of a suitable lever which may be engaged with any of a series of radial openings 21 with which the nut is provided. The clamping members are provided 85 with studs 22 in their opposing ends which engage in the guide members 2. A bolt rod 23 connects the arms of the clamping members and passes through the guide. 90

By means of the screw 17, the nut and the blocks, the clamping member 11 may be forced toward the fixed clamping member 4 to cause the members of the guide, at the 100 joint, to be firmly secured between said clamping members and to the guide plate, so that the guide members may be maintained in exact vertical alinement with each other and casual movement or deflection of 105 the guide effectually prevented, thereby averting accidents such as are occasioned by the guides of a mining shaft or elevator shaft getting out of plumb. My improved clamping device also greatly facilitates 110 repairs of the guide.

In Fig. 3 of the drawings I show a modifi-

cation in the construction of the guide members in which the arm is cross shaped as at 24.

In Fig. 4 I show another modification in which the arm 25 of the clamping member is coextensive in width with the base 5^a.

In Fig. 6 I show another modification which the adjusting nut 20^a is solidly fixed to the outer end of the adjusting screw 17 and one of the blocks dispensed with, only one block 16^a being employed, which has a threaded bore with which the adjusting screw is threadedly engaged.

While I have herein described and shown preferred embodiments of my invention, I would have it understood that changes may be made in the form, proportion and construction of the several parts without departing from the spirit of my invention and within the scope of the appended claims.

Having thus described my invention, I claim:

1. In combination with a guide plate and a guide extending thereacross, a fixed clamping member secured on the guide plate and

bearing against one side of the guide, an adjustable clamping member mounted for movement on the guide plate and bearing against the opposite side of the guide, and means to adjust and hold said adjustable clamping member, the said clamping members having arms arranged at right angles thereto and positioned in recesses in the sides of the guide.

2. In combination with a guide plate and a guide extending thereacross, a fixed clamping member secured on the guide plate and bearing against one side of the guide, an adjustable clamping member mounted for movement on the guide plate and bearing against the opposite side of the guide, each of said members having a right angularly disposed arm arranged in a recess on the adjacent side of the guide, a bolt connecting said arms and passed through said guide, and means for adjusting the movable clamping member.

In testimony whereof I affix my signature.

HOMER MAURICE LAMB.
